(57) **CLAIM**

The ornamental design for a vessel for a candle, as shown and described.

DESCRIPTION

FIG. 1 is a top perspective view of a vessel for a candle, illustrating my new design;

FIG. 2 is a bottom perspective view;

FIG. 3 is a front elevational view;

FIG. 4 is a rear elevational view;

FIG. 5 is a left elevational view;

FIG. 6 is a right elevational view;

FIG. 7 is a top plan view; and,

FIG. 8 is a bottom plan view.

The candle wick illustrated in broken lines is environmental structure that forms no part of the claim. All other broken lines represent the bounds of the claim and form no part of the claimed design.
